UNITED STATES PATENT OFFICE.

CRAWFORD C. LOOMIS, OF ILION, NEW YORK, ASSIGNOR TO REMINGTON ARMS COMPANY, INC., A CORPORATION OF DELAWARE.

FIREARM.

Application filed September 11, 1924. Serial No. 737,023.

To all whom it may concern:

Be it known that I, CRAWFORD C. LOOMIS, a citizen of United States, residing at Ilion, county of Herkimer, State of New York, **5** have invented certain new and useful Improvements in Firearms, of which the following is a specification.

This invention relates to firearms and is particularly adapted for use on firearms of **10** the type shown in the Patents 719,955, Feb. 3, 1903 and 789,755 May 16, 1905, to John D. Pedersen. These patents disclose a firearm of the magazine type, particularly adapted to accommodate shot shells. Such **15** shells or cartridges are loaded into a tubular magazine from the rear end thereof, and are retained therein by a stop or lug consisting of a stiff spring attached to the "carrier." As the forearm and action bar **20** are retracted in the operation of loading the gun, the carrier is rotated to release the rearmost cartridge from the stop, and said cartridge then slides rearwardly onto a suitably constructed part of the carrier. On **25** the forward movement of the action bar the carrier is usually rotated to elevate the cartridge into alignment with the chamber, and the stop lug is thereby brought into position to engage the base of the next cartridge. **30** The lifted cartridge is pushed into the chamber by the breech block. The firing pin and cocking head were retracted on the rearward movement of the action bar, and as the action bar and breech block reach **35** their final forward positions the action bar is locked against another rearward movement until the hammer has moved forward to fire the shell in the chamber.

In this gun as hitherto constructed, the **40** action bar lock has been released simply by the forward movement of the hammer, whether or not the shell in the chamber is fired. Now it sometimes happens that the primer mixture and the powder will be **45** ignited by the blow of the hammer, but the powder will burn abnormally slowly, and a very appreciable time will elapse before the powder gas develops sufficient pressure to expel the shot or bullet. Such a shell or **50** cartridge is known as a "hang fire." The shooter, holding the gun against his shoulder partly by means of the forearm, naturally quickly draws the forearm and action bar rearwardly the instant the action bar lock is released. If the shell hangs fire it

may explode with the breech partly or wholly open, or even when entirely removed from the gun, with consequent serious injury to the shooter or the gun or both.

One object of my invention is to provide **60** an action bar lock which for its release requires not only the forward or firing movement of the hammer, but the firing of the shell in the chamber, and the subsequent recoil of the gun. **65**

A further object of the invention is to improve the construction of the action bar locking mechanism.

A further object of the invention is to provide an action bar locking pin having a **70** rectilinear movement in a guide way in the breech block.

With these and other objects in view my invention consists in the novel combinations and arrangement of parts hereinafter described and illustrated in the drawings, in which:

Fig. 1 is a vertical longitudinal section thru the receiver of a firearm having my invention applied thereto. **80**

Fig. 2 is a horizontal section on the line 2-2 of Fig. 1, showing the action bar held by the action bar locking devices.

Fig. 3 is a view similar to Fig. 2, but showing the action bar locking devices in **85** ineffective position.

Fig. 4 is a perspective of the action bar locking mechanism.

The receiver 10 which encloses the main parts of the operating mechanism, has an **90** opening 11 at the bottom to permit of loading and ejecting the shells. The breech block 12 when at the limit of its forward movement engages a recoil shoulder 13 on the receiver frame, locking the breech block **95** against rearward movement until released from said shoulder. The breech block is recessed to receive a firing pin 14, inserted therein from the rear, and terminating at its rear end in a cocking head 15 comprising **100** a shoulder 16 adapted to be engaged by a sear 17, which is held in engagement with shoulder 16 by the usual sear spring. The sear comprises a laterally extending foot 19 which extends under the forward end of the **105** trigger 20.

The breech block is adapted to be reciprocated by an action bar 21 connected at its forward end with the usual forearm 211. The action bar, which is reciprocated in a **110**

longitudinal guiding recess 212 in the receiver wall, comprises a laterally extending lug 22 which engages a slot or cam groove 23 in the breech block. When the action is closed the breech block is in the position shown in Fig. 1, the upper rear end thereof being in engagement with the recoil shoulder 13 and the action bar lug resting at the lower end of the cam slot 23. When the action bar is retracted the action bar lug 22 engages the cam face 231 and lowers the rear end of the breech block to clear the recoil shoulder 13, the breech block turning on trunnions 232 on the receiver, which are received in half journals formed in the front end of the breech block. When the action bar lug 22 reaches the rearward part of the cam slot 23 the breech block is clear of the recoil shoulder and moves rearwardly with the action bar.

As hereinbefore pointed out, it is necessary to lock the action bar and breech block against retraction until the gun is fired. For this purpose the action bar lug 22 comprises a notch 24 adapted to receive the end of a locking pin 25 guided for rectilinear movement in a transverse hole in the breech block. The head of the pin 25 comprises a lateral projection 27 which is received in a recess 28 in the breech block and prevents the pin from turning. Opposite the projection 27 on pin 25 is a slot 29 adapted to receive the end of a locking pin operating lever 30, pivoted in the breech block at 31. The rear end of lever 30 is turned inwardly, at the rear of the sear 17 and comprises a part 32 of reduced thickness, adapted to be engaged by a depending and laterally extending foot 321 on the sear, whereby the sear is locked against movement to firing pin releasing position unless the action bar lock is effective. A head 33 pivoted to the end of lever 30 is pressed toward a vertical flange 34 on the cocking head 15 by a spring 35 and by engagement with said flange moves the action bar lock pin 25 to effective position. A finger button 36 pressed inward by a spring 37 overlies the lever 30 at a point between the pivot 31 and the cocking head engaging end of said lever, and extends thru the receiver wall. Spring 35 is stiffer than spring 37 and normally holds the action bar locking pin in effective position, but the action bar may be manually released by pressing button 36 inward.

It is important for the purpose of preventing injury to the shooter or the gun from the explosion of a "hang fire" shell after the breech has been partly or fully opened that the action bar be locked, not only until the firing pin has moved forward but until the shell is actually discharged. To this end the engagement between the action bar 21 and the lock pin 25 is such that the lock pin will remain in engagement with

the action bar until the gun recoils on firing, or until the shooter moves the action bar slightly forward. The locking face 251 of lock pin 25 is slightly undercut as clearly shown in Figs. 2, 3, and 4, and the locking face 221 of the action bar lug is similarly shaped, so that a short forward movement of the action bar relative to the lock pin is necessary to disengage the two. The shooter normally holds the gun against his shoulder by pulling rearwardly on the forearm and action bar, thus a secure engagement of the pin with the action bar is insured. If the trigger is pulled with no shell in the chamber the action bar will remain locked until the rearward draft thereon is momentarily relieved. When a shell is fired the recoil imparts a sharp backward movement to the gun itself, and the lock is disengaged without the user consciously releasing the action bar. The danger of opening the breech before a hang fire shell has fired, is thus eliminated, since there will be no recoil until the shell actually fires, and a special and unusual manual operation is necessary to release the lock in the absence of a recoil.

It is manifestly of importance that the pin 25 move transversely in a straight line, hence this pin is made separately from its operating lever 30, and a tongue and slot connection between them is provided, in place of the integral lever and locking pin shown in the Pedersen Patent 789,755, above mentioned.

The operation of the mechanism is as follows: Assume that the gun is loaded and cocked, and the breech closed. Locking pin 25 stands in the path of lug 22 preventing the rearward movement of the action bar 21, relative to the breech block, which is necessary to lower the breech block from engagement with the recoil shoulder 13. The rear end of lever 30 occupies a slot in the receiver, so that button 36 is pushed outward, the sear is free from the locking part 32 of lever 30, and the parts are so held by the engagement of pivoted member 33 with the flange 34 on the cocking head 15.

If now the piece is fired, the flange 34 moves forward out of the path of pivoted member 33, and the recoil of the gun disengages the locking face 251 from the face 221 on the action bar lug. The lever 30, thus released, is rocked about its pivot 31 by spring 37, withdrawing pin 25 from the path of action bar lug 22. As the action bar is drawn back the breech block moves downward and rearward, the cocking head is drawn back, and the flange 34 encounters the pivoted head 33 on lever 30, but lever 30 is prevented from swinging on its pivot by the receiver wall, until near the end of the rearward movement of the breech block, when the rear end of lever 30 enters a groove in the receiver wall, and the sear 17 is moved

to cocking head engaging position by its spring 18.

On the forward movement of the breech block the rear end of lever 30 is again moved inward by engagement with the receiver wall, and ledge 32 passes under the foot 171, preventing the cocking head disengaging movement of the sear until the breech is fully closed and locked. At the end of the forward movement of the action bar, the breech being closed, as the breech block is moving upwardly, its rear end in contact with the locking shoulder 13, lever 30 is moved opposite a groove in the receiver wall and it moves outwardly into said groove, releasing the sear, pushing out the finger button 36, and locking the action bar. One cycle of the operation is now complete.

The invention is not to be considered as limited to the precise construction herein described and illustrated in the drawings, but is to be construed as covering all equivalent devices falling within the scope of the appended claims.

25 I claim:—

1. In a firearm comprising a reciprocating breech block and an action bar for operating said breech block, means effective to lock said action bar against retraction until it has moved slightly forward, said means comprising a pin adapted to slide in a transverse hole in said breech block, a slot near one end of said pin, a pivoted lever in engagement with said slot, and means for operating said lever.

2. In a firearm comprising a reciprocating breech block, an action bar for operating said breech block and a firing mechanism, means controlled in part by said firing mechanism for locking said action bar when the firing mechanism is in firing position, and means associated with said action bar and said locking mechanism for preventing the release of said action bar for retraction until the action bar has first moved forward relative to the locking mechanism.

3. In a firearm comprising a reciprocating breech block, and an action bar for operating said breech block; a firing pin comprising a cocking head mounted for reciprocation in said breech block, an action bar locking mechanism effective to lock the action bar against retraction until it has moved slightly forward, said locking mechanism comprising a locking pin and a lever for operating said pin, a device associated with said lever adapted to engage a part of said cocking head when said head is in retracted position, thereby maintaining said locking pin in locking engagement with said action bar.

4. In a firearm comprising a reciprocating

breech block containing a firing pin and an action bar comprising interengaging members associated with said action bar and said breech block, said means being for operating said breech block, locking means for said action bar effective when the firing pin is retracted and requiring for its release both the forward movement of the firing pin and a slight forward movement of the action bar from its lock engaging position.

5. In a firearm comprising a reciprocating breech block containing a firing pin and an action bar for operating said breech block, locking means for said action bar comprising a locking lug on said action bar and a locking pin movable transversely in said breech block, and adapted to engage said locking lug and to release said lug when retracted into said breech block, the engaging surfaces of said action bar lug and said locking pin being such that a slight forward movement of the action bar relative to the locking pin is necessary to release said pin for retraction into said breech block.

6. In a firearm comprising a reciprocating breech block containing a firing pin and an action bar for operating said breech block, locking means for said action bar comprising a locking lug on said action bar, a locking pin movable transversely in said breech block and adapted to engage said action bar locking lug, means for preventing rotation of said pin while permitting longitudinal movement thereof, an operating lever, a slot in said locking pin adapted to receive one end of said lever, and a spring pressed head pivoted to said lever and adapted to engage a part of said firing pin when said pin is retracted to firing position, whereby said lock pin is moved to locking position.

7. In a firearm comprising a reciprocating breech block containing a firing pin and an action bar for operating said breech block, locking means for said action bar comprising a locking lug on said action bar, a locking pin movable transversely in said breech block and adapted to engage said action bar locking lug, means for preventing rotation of said pin while permitting longitudinal movement thereof, an operating lever, a slot in said locking pin adapted to receive one end of said lever, and a spring pressed head pivoted to said lever and adapted to engage a part of said firing pin when said pin is retracted to firing position, whereby said lock pin is moved to locking position, and manual means for moving said lever to unlocking position when the firing pin is in retracted position.

CRAWFORD C. LOOMIS.
